APPARATUS FOR VERIFYING STATISTICAL DATA

John N. Wheeler, Hawthorne, N. Y., assignor to
 International Business Machines Corporation,
 New York, N. Y., a corporation of New York

Application September 20, 1940, Serial No. 357,541

4 Claims. (Cl. 73—54)

This invention pertains broadly to statistical systems, and more specifically relates to apparatus for verifying statistical data recorded upon records, in the form of index marks, which records are adapted for use in statistical machines, the said index marks controlling the statistical operations of the machines.

It has been suggested to employ a continuous photographic film record having coded data designations formed thereon, in the individual frames or areas of the film record, for controlling the operations of various statistical machines. The individual frames or areas of data designations, which designations may be in the form of photographic spots or marks, are formed at successively spaced intervals along the film and will be referred to as individual records. It has also been suggested to employ colored photographic film records having the data designations formed thereon in different colors for controlling the operations of statistical machines. In the present invention the said individual records will be shown to comprise groups of data designations in the form of discrete and differently colored spots or marks which are disposed in different positions in different columns on the photographic film records, so as to represent by their relative positions thereon the values thereof. The photographic records described in the present application are claimed in a separate and co-pending application, Serial No. 282,209, filed June 30, 1939 now Patent No. 2,268,499 issued December 30, 1941.

The subject matter of the instant application relates solely to the means for verifying the photographic records bearing the differentially positioned and colored index marks or spots. Means are provided whereby the verifying or comparing data is set up and stored for controlling the verifying operations. Such means, in the instant disclosure, comprise manually operable keys, which upon depression are latched in a depressed position for maintaining the selection of control circuits associated with the said keys. Differentially timed impulses, which are initiated by suitable record sensing means upon sensing the photographic marks or spots, are routed through the various verifying circuits set up by the said keys, by means of a commutation device operated in synchronism with the record sensing means, whereby control relays are energized upon the disagreement of the sensed and stored data. Indicating lamps are provided, and the energization of which are controlled by the said relays indicating the numerical and color values of the

5 data sensed on the records, which data are in disagreement with the data set up in the verifying keyboard. Additional means are provided to mark or perforate those records containing data thereon found to be in error.

10 Therefore, an object of the present invention resides in the provision of means for verifying the color and data values of the colored data designations which are sensed on individual control records.

15 Another object of the present invention resides in the provision of means for indicating the relationship of both the color and data values of the compared or verified data designations.

20 Another object of the present invention resides in the provision of means for normally preventing further verifying operations of the machine upon the detection and indication of a disagreement between the sensed and verifying data designations.

25 Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a fragmentary section of a portion of the machine control record.

30 Fig. 2 is a diagrammatic view of the record analyzer.

Fig. 3 is a sectional view of the record feeding and analyzing means.

35 Fig. 4 is a plan view of the record feeding and analyzing means.

Fig. 5 is a detail view of the record feeding means and shows partly in section one type of record marking means.

40 Fig. 6 is a sectional view of the keyboard section.

Fig. 7 is a detail view of the keyboard section showing the key and motor bar release mechanism.

Fig. 8 is a timing chart of certain elements of the machine.

45 Figs. 9a and 9b are a wiring diagram showing the circuit connections of the machine.

Photographic control records

50 Referring now to Fig. 1, the photographic control element 20 shown therein is a fragmentary section of a continuous strip of photographic color film, provided with the usual feed apertures 24, upon which film are formed a plurality of individual records a to e comprising groups of data

designations 22 in the form of discrete and differently colored control spots. One type of color film which is suitable for the purpose described in the instant application is the "Agfacolor" film, which comprises a single unitary film structure consisting of a support upon which is coated in thin superimposed layers a plurality of light sensitive emulsions, each particularly sensitive to one of the primary colors. By exposing such a film to a colored object, three separate color records are recorded simultaneously, each sensitized layer recording the image to which it is color-sensitive. The color formation is brought about by the development of the film. Assume that the film 20 has been suitably exposed to record the data thereon in color, and that the color formation of the data as designated is brought out by development of the recorded film.

The spot representation 21 on each record represents supplemental control data, and the spot representations 22 represent amount data. The data represented by the reference character 23 is shown merely for interpreting the associated coded control spots and are not used for controlling machine operations. Assume that the data shown in the individual records *a* and *b* are formed in red color, the data in record *c* in blue, the data in record *d* in green, and the data in record *e* in black.

The spot representations 21 and 22 are photographic machine control spot representations, and each set of numerical data comprises one or more control spots in such relative position, in different columnar areas, upon the film record as to represent by their relative position thereon the numerical control value thereof. In practice and according to the embodiment shown, such numerical spot representations are shown on the film in index point relation in general conformance with the manner in which index perforations are disposed on perforated record cards in the Hollerith accounting system. That is, the differential position of a control spot representation delineates the numerical value of a particular numeral. This will be clear by referring to the figure and particularly record *a*, wherein the data represented by the designations or control spots 22 represent the amount twenty-seven.

It will be understood that the completed film has photographic reproductions thereon at successively spaced intervals along the film, and that the reproductions are in extremely compact form, accordingly, a large quantity of statistical information can be placed on an extremely small controlling record.

Method of analyzing color of data designations

Referring now to Fig. 2, the method of analyzing the colored control spots formed on the film will now be explained briefly. Assume that the film 20 is advanced in the direction shown by the arrow past the sensing station which is represented by an aperture 25 in the opaque member 26, and that the color of a control spot presented to the said sensing station is red. Light rays emanating from a suitable source 27 are directed by the condenser 28 to the aperture 25 to permeate the section of the film presented to the said aperture. The red rays transmitted by the control spot are directed to different photocells 29a, 29b and 29c, by means of the light conducting means comprising a three-way quartz rod member 30. Suitable light ray filters 31 to 33 are disposed between the individual legs of the quartz rod member and the associated photocells. As-

sume that the filter 31 is a cyan color filter designed to pass the different colored rays excepting red rays which are absorbed by this filter, that the filter 32 is a magenta color filter permitting the colored rays, with the exception of green to pass therethrough, and that the filter 33 is a yellow color filter permitting the colored rays, with the exception of blue, to pass therethrough.

Now, since the red light rays are directed by the individual legs of the quartz member 30 to the individual filters 31 to 33, it is understood that the said rays are permitted to pass through the magenta and yellow filters to impinge upon the associated photocells 29b and 29c, respectively, but are absorbed by the cyan filter so that no light rays are transmitted to the associated photocell 29a. Upon presentation of a blue control spot to the sensing station, it is seen that the cyan and magenta filters permit the rays to be transmitted to photocells 29a and 29b, respectively, whereas no blue light rays are transmitted by the yellow filter to the photocell 29c, and upon sensing a green control spot, light rays are transmitted to photocells 29a and 29c but not to photocell 29b. In the event that a black control spot is presented to the sensing station, no light rays are transmitted to any of the three photocells, namely, 29a to 29c.

Suitable amplifiers 34 are connected to the said photocells 29a to 29c (see Fig. 9a), in a manner well known in the art, so that it is considered necessary only to state that when light rays are impinging on the photocells the associated amplifiers are conditioned so that no current flows in its output circuit, whereas, when no light rays are transmitted to the photocells the associated amplifiers are conditioned so that current flows in the output circuits thereof as long as the light rays do not impinge thereon. The purpose of this arrangement will be understood as the description progresses.

Film feeding and sensing means

Referring now to Figs. 3, 4 and 5, the photographic color film 20 is shown disposed on a supply spool or reel 35. The film is attached to a take-up reel 36, and may be advanced by suitable driving connections cooperating with shafts 37 and 38, by means of suitable film feeding sprockets 39 and 40 secured to the said shafts, respectively, which sprockets cooperate with the film feed apertures 24 in the film. The film is fed past the analyzing station comprising the sensing aperture 25 and transilluminated by the light rays emanating from the light source 27 and directed thereto by the condenser 28. The said scanning aperture is arranged to present an opening sufficient to permit the scanning of a single transverse row of data or control spots only, and is provided to extend transversely across the film record to any desired extent so as to permit the desired columns on the film to be sensed. The reference characters 29a, 41a, and 42a designated in Fig. 4 represent the plurality of rows of photocells which are disposed at the analyzing station and controlled by the light rays impinging thereon. Each row of photocells, in the present illustration, comprises three photocells, for example, in Fig. 3, they are designated 29a to 29c. It is understood for each columnar area on the film, three individual photocells are provided and arranged as described. For each row or order of photocells, a three way light conducting member 30 is provided, said member comprises

a quartz rod member having three conducting legs for transmitting the light rays from the sensing aperture 25 to the associated photocells. The said quartz members are suitably supported by the block 43, and as mentioned the legs thereof extend from each photocell to the analyzing station where the common legs are positioned adjacent to one another along the sensing aperture. The spacing of the common legs of the quartz members along the said aperture is so arranged that each leg is positioned opposite one of the columns of control spots disposed on the film. In this manner, the light rays directed to the sensing aperture can be conducted to the associated photocells to condition the latter for machine control operations during the sensing operations.

As mentioned before, individual color filters 31 to 33 are provided to be interposed between the individual legs of the quartz members 30 and the associated photocells. In Fig. 3, the color filters designated 31 to 33 are the cyan, magenta and yellow color filters referred to hereinabove for the purposes set forth. It is understood that the three filters are provided for each order and interposed between the legs of the quartz members and associated photocells as shown in Fig. 3.

The film feeding means and control means therefor, comprise generally the clutch magnet 44 and the associated pivoted armature 45 to which is secured a latch lever 46 normally engaging an extension 47 of the member 48 secured to shaft 38, and the clutch pawl 49 pivotally supported by member 48 and normally disengaged from the clutch element 50 by means of the said latch lever. Upon energization of magnet 44, the latch lever 46 is caused to release the pawl 49 and engage the clutch element 50 which is rotatably mounted on shaft 38 and rigidly secured to gear 51 which is driven by suitable means such as the gear 52, drive pulley 53 and the associated driving connection 54. Thus it is seen, whenever the driving connections are operated, and the magnet 44 energized, that shaft 38 is rotated and in addition thereto gear 55, which is secured thereto, to rotate gears 56 and 57 the latter being secured to shaft 37, thereby rotating said shaft and causing the respective feed sprockets 40 and 39 to feed the film to the analyzing station. The control spots disposed on the film are then effective to modify the light rays emanating from the light source as described hereinabove for controlling the conditioning of the associated photocells.

It should be mentioned that film supply control contacts 60 (Fig. 5) are provided and adapted to be closed by the suitably pivoted lever 61 as long as the film is presented to the analyzing station; however, when the film supply is exhausted the said lever swings to the left as viewed in Fig. 5 to open the contacts 60. Opening of contacts 60 exercises a controlling function whereby further machine operations are prevented upon exhaustion of the film supply in a manner well known in the art. Such a controlling function is described in U. S. Patent No. 2,196,166. On shaft 37, a plurality of cams 62 are provided (only one of which is shown in Fig. 3) for controlling the contacts C1 to C6 (Figs. 9a and 9b) so that the said contacts are closed at different times during the machine cycle as indicated in Fig. 8.

Associated with the film feeding means are suitable marking means for marking the individual frames or records of the film which are found to be in error, so that they can be readily

located and replaced by corrected records. The marking means shown comprises punching means (see Fig. 5) for notching the records which are in error. In Fig. 1, a notch 63 is shown formed in record e and is suitably disposed along the marginal edge of the film record. The said marking means is located below the sensing station and consists of a punch 64, mounted in a block 65, which punch is held in the position shown by means of a compression spring 66. The punch die 67 is shown as an integral part of the member 26. The operation of the punch 64 is controlled by magnet 68, which upon energization attracts the armature 69 secured to the pivoted lever 70 to cause the said lever to engage and operate the punch 64. In this manner, the individual records can be marked whenever the magnet 68 is energized. The circuits for controlling the energization of magnet 68 will be described hereinbelow. Contacts 71 and 71a are provided and suitably positioned in the path of the lever 70 so that upon energization of magnet 68 the said lever will cause the contacts 71 to be opened and contacts 71a to be closed at the moment the armature 69 engages the core of the said magnet. The purpose of the said contacts will be understood as the description progresses.

Keyboard section

Referring now to Figs. 6, 7 and 9a the keyboard section is shown to comprise a plurality of columns or orders of individual keys. The number of keys in each order can vary as desired, however, in the instant case an individual key is provided for each index mark or point position in the individual columns of the records, and for each color designation appearing on the film records. The purpose of the keyboard section is to provide means for storing the desired comparing data.

Provision is made whereby upon depression of the individual keys 75 against the action of the associated springs 76, they are held latched in the depressed positions by the related latch bars 77 (of which one for each order of keys is provided). Each key bar is provided with a V-shaped conducting portion 78 adapted to engage normally the related contacts 79. This connection will be referred to as contacts A on the wiring diagram. Upon depression of any selected key 75, the associated conducting portion 78 is disengaged from the related contacts 79, or stated in other words, upon depression of any selected key the associated contacts A (see wiring diagram) are opened.

The verifying operations of the machine are initiated by the manual operation of a motor bar 80, the depression of which causes the contacts 81 to be closed. By means of a latch lever 82 the depressed bar is maintained so, due to the engagement of the stem 83 of the bar with the said latch lever. Upon completion of the verifying operations means are provided, such as solenoid 84, to be energized to restore the motor bar to its normal position. It is seen that energization of the solenoid causes the pivoted latch member 82 to be partially rotated in a clockwise direction upon displacement of the solenoid plunger by means of the link 85 thereby releasing the latched stem 83 of the motor bar.

During the said rotation of latch member 82 and after the release of the motor bar the link 86 causes lever 87 to be partially rotated and in turn to rotate the shaft 88 in a counterclockwise

direction. Rotation of shaft 83 effects displacement of the arm 89 (secured to said shaft) and transverse bail 90, which bail, upon being rocked, thrusts the latch bars 71 forwardly (to the left as viewed in Fig. 6) releasing any depressed keys which have been latched down. For a more detailed description of this well known type of keyboard reference may be made to U. S. Patent No. 2,147,626.

Operation of the machine

Referring now to Figs. 8, 9a, and 9b, the description of the operation of the machine will be given. Assume that, upon closure of switches S1 and S2 the light source and amplifiers 34 are provided with suitable potentials, that suitable driving means are effective to rotate continuously the driving gear 52, and furthermore, that the photographic film 20 is properly arranged in the feeding and sensing unit.

The first step in the operation of the instant verifying machine comprises setting up the verifying data upon the keyboard section. The selected keys 75 representing the verifying data are locked in the depressed positions, as described hereinabove, to maintain the associated A contacts open during the verifying operation. The individual columns of contacts shown in Fig. 9a, and indicated U, T, and H, are controlled by the units, tens and hundreds order keys 75 of the keyboard section, respectively. It is seen that numerical and color designating keys are provided. For each record to be verified, the number and color keys are depressed in accordance with the data which is assumed to be recorded and represented on the record and the color designation of the data representing spots. The corresponding contacts A of each order or column of contacts are connected individually to the pickup coils of the associated relays of the groups of relays designated UR1 to UR14, TR1 to TR14, and HR1 to HR14.

The stationary conducting segments 100 of a suitable commutation device 99 are connected individually to the groups of pickup coils of all the orders representing the different numerical and color designations, so that upon rotation of the conducting brushes 101 the pickup coils of relays UR1, TR1, HR1, UR2, TR2, HR2, etc. associated with the individual contacts A are connected successively to the common conducting ring 102 and the pickup coil of relay R18. It should be mentioned that the brushes 101 of the commutation device are mounted on the shaft 37 of the film feeding unit (Fig. 3) and arranged to engage the conducting segments 100 in synchronism with the presentation of the index point positions of the individual records to the sensing station. For example, when the "5" index point positions of a record are presented to the sensing station, the brushes 101 are arranged to engage the "5" conducting segment which is connected to the pickup coils of relays UR5, TR5, and HR5, which coils in turn are connected to the individual "5" contacts A of each order. In this manner, the stored data in the keyboard section can be read out in timed relationship with the sensing of the data recorder on the individual records.

The data verifying capacity of the instant machine as disclosed is limited to three orders. However, it is evident that the capacity can be expanded to any desired extent by providing for each order of data to be verified the connected control elements shown, in the circuit diagram.

It was described hereinabove how the different colored spots on the records are analyzed and con-

trol the conditioning or activation of the photo-cells. Upon sensing red spots in the columns on the records, the photocells 29a, 41a, and 42a, for example, are not activated by the light rays, and thereby render the connected amplifiers 34 conductive to energize the associated control relays AR, BR and CR. Upon sensing the green spots the relays AG, BG and CG are energized, and upon sensing the blue spots, the relays AB, BB, and CB are energized. It was stated, whenever black spots are sensed, no light rays are transmitted to the photocells. Therefore, it is seen that all the said relays AR, AG, AB, BR, etc. are energized.

The said relays are energized at the different times the control spots are sensed to establish the different data verifying circuits. For example, assume that one of the records to be verified has recorded thereon in red colored spots, the number 125, and assume further that the said numbers and the said color designations are set up in the keyboard section so that the red contacts A and the corresponding "1," "2," and "5" contacts A of the hundreds, tens and units orders, respectively, are held open during the ensuing machine cycle. Now, upon depression of the motor bar or start key 80, the contacts 81 are closed to complete a circuit from conductor 103 to contacts 81 and R18b, coil of magnet 44 to conductor 104, energizing said magnet, and thereby effecting feeding of the record past the sensing station. Upon sensing the differentially disposed data representing spots, the relays AR, BR and CR are energized at the 5, 2, and 1 points in the machine cycle respectively, to effect operation of the associated contacts AR1 to AR4, BR1 to BR4, and CR1 to CR4.

Since the brushes 101 of the commutation device are positioned in timed relationship with the feeding of the record, the "5," "2," and "1" conducting segments 100 which are connected to the pickup coils of relays UR5 to HR5, UR8 to HR8, and UR9 to HR9, respectively, are engaged successively at the times in the cycle the contacts CR1, BR1, and AR1 are closed. It is seen that, under the assumed conditions, and due to the connections of the described control circuits, no circuits are completed from conductor 103 through the closed contacts AR1, BR1, and CR1, conductors 105, and contacts A to the pickup coils of the relays UR1 to UR11, TR1 to TR11, HR1 to HR11, R18 and conductor 104 to effect energization of any of the said relays. Obviously, the only circuits which could be energized under the assumed conditions are open due to the operated "1," "2," and "3" contacts A. Due to the arrangement of the verifying circuits the numerical data values are verified first, after which the verification of the color designations is effected, upon the closing of contacts AR2, AR3, BR2, BR3, CR2, CR3 and opening of contacts AR4, BR4, and CR4, circuits are completed to effect energization of relays R20, R24, and R28. One of the circuits can be traced as follows: conductor 103, contacts AR3, AB3 and coil of relay R20 to conductor 104. Holding circuits for the said relays are established immediately through the associated contacts R20a, R24a, R28a, which are connected by a common conductor 106 to the normally closed cam contacts C6. Contacts R20b, R24b and R28b are also closed to effect partial completion of the color verifying circuits upon closure of cam contacts C2. However, since the color values to be verified are in agreement, no circuits are completed by the 75 commutator device when the brushes 101 thereof

traverse the "11," "12," "13" and "14" conducting segments 100 associated with the color designating keys and contacts of the keyboard section, and corresponding control relays.

It should be stated that the cam controlled contacts C1 to C4 are closed successively (see Fig. 8) and in synchronism with the successive engagement of the brushes 101 and the "11," "12," "13," and "14" conducting segments 100. In this manner, the different color verifying circuits can be established. The purpose of this arrangement will be understood as the description progresses.

Near the end of the machine cycle, the cam contacts C6 are opened and cam contacts C5 are closed for the duration of one point in the machine cycle. Opening of contacts C6 breaks the holding circuits to relays R20, R24 and R28, thus restoring the said relays to the normal deenergized condition; and upon closure of contacts C5 the key release magnet 84 of the keyboard section is energized to release the data keys and the motor bar latched in the depressed position. Release of the motor bar causes deenergization of the feed control magnet 44 due to the opening of contacts 81, thus preventing further record feeding operations until the motor bar is depressed again to close the said contacts 81.

Now, assume that the data values set up in the keyboard section and the data recorded and sensed on one of the records are not in agreement. For example, assume that the set up in the keyboard section represents the data 125, and that the color designations represented therein are red, whereas the data recorded on the said record is 126 and the colors of the data representing spots are blue. The motor bar is depressed and contacts 81 are closed as before to effect energization of the feed control magnet 44, thereby rendering the record feeding means and commutator device operative. Since the sensed data, namely 126, and verifying data, namely 125, are not in agreement the following circuits are established. At the time the spot in the "6" index point position in the units column on the record is sensed to effect energization of the relay AB, the brush 101 is engaging the "6" conducting segment 100 which is connected to relays UR4, TR4 and HR4, and the associated "6" contacts A; and since the "6" contacts in the units order of the keyboard section is closed, a circuit at this time is completed from conductor 103 to contacts AB1, conductor 105, "6" contact of the units order of the keyboard section, pickup coil of relay UR4, "6" conducting segment 100, brushes 101, conducting ring 102, pickup coil of relay R18, and conductor 104, energizing the said relays UR4 and R18. Holding circuits for the said relays are established from conductor 103, contacts 107 of a release key, contacts 71, contacts UR4a, R18a, and related holding coils of relays UR4 and R18, respectively, to conductor 104. The following circuit is also established from conductor 103 to the "6" indicating lamp 110 of the units order, contacts UR4b to conductor 104, energizing said lamp and indicating that the number "6" sensed in the units column on the record is in disagreement with the verifying data.

Continuing now with the color verification, it is understood upon sensing the blue data designation spots that the contacts AB2, AB4, BB2, BB4, CB2, CB4 are closed and contacts AB3, BB3, and CB3 are opened upon energization of the relays AB, BB, and CB, respectively, to establish circuits to energize the relays R21, R25, and R29 of the group of relays R19 to R30. Holding circuits are

established through the contacts R21a, R25a, R29a and the normally closed cam contacts C6. Contacts R21b, R25b and R29b are closed so that during the latter part of the cycle the color values of the data can be verified. It is understood that at the time in the cycle, when cam contacts C3 are closed, the brush 101 engages conducting segment "13," and since the contacts A representing blue data designations are closed the following circuits are completed, upon closure of cam contacts C3: conductor 103, contacts C3, contacts R21b, R25b, R29b, conductors 109, contacts A representing the blue data designations of all the orders of the keyboard section, pickup coils of relays HR13, TR13 and UR13, conducting segment "13," brushes 101, conducting ring 102, pickup coil of relay R18 and conductor 104, energizing relays UR13 to HR13 (it is remembered in the present example relay R18 is energized and locked). Holding circuits for the said relays are established from conductor 103, contacts 107 of reset key RK, contacts 71, contacts UR13a, TR13a, HR13a, and related holding coils of relays UR13 to HR13, respectively, to conductor 104. The described holding circuits are maintained until contacts 107 or 71 are opened. Upon energization of the said relays UR13 to HR13, the associated contacts UR13b to HR13b are closed to permit the associated indicating lamps to be energized, thus indicating that the blue data designation spots sensed in the units, tens and hundreds columns are in disagreement with the verifying data.

Near the end of the cycle the cam contacts C6 are opened as mentioned hereinabove, to break the holding circuit for relays R21, R25 and R29 and restoring the said relays to the normal deenergized condition. Cam contacts C5 also are closed near the end of the cycle to effect energization of the magnet 84 and release the latched data keys and motor bar. It is seen however, that this operation is not effected whenever relay R18 is energized, since contacts R18d are open whenever disagreement of the sensed and verifying data occurs.

When no disagreement exists between the sensed and stored data, the feed control magnet 44 is deenergized near the end of each cycle by virtue of the opening of contacts 81. However, it is noted in cases of disagreement of the said data additional provision is made in the feed magnet circuit to deenergize the magnet 44 and prevent further energization thereof by means of the opened contacts R18b.

Upon determination by the operator whether the indicated error exists in the sensed film record or in the keyboard set up the error key EK or the release key RK is depressed. If an error was made in setting up the stored or verifying data the release key RK is depressed to break the holding circuit for the groups of relays UR1 to UR14, TR1 to TR14, and HR1 to HR14 and relay R18, by opening the contacts 107, thus restoring these circuits to the normal deenergized condition, whereby further verifying operations can be effected as described.

Upon deenergization of relay R18 and continued depression of the release key RK to maintain the contacts 107a closed, a circuit is established from conductor 103 to contacts 107a, conductor 103a, contacts R18d, magnet 84 to conductor 104, energizing said magnet to effect releasing of the depressed keys of the keyboard section.

If the error exists in the sensed film record, the error key is depressed to energize the error magnet 68. Energization of the said magnet causes

the said film record to be notched as indicated in Fig. 1 by the reference character 63.

Upon operation of the error magnet 68 the contacts 71 are opened to break the holding circuits to the groups of relays UR1 to UR14, TR1 to TR14, and HR1 to HR14 and R18, thus restoring these energized circuits to the normal deenergized condition. Contacts 71a are closed at this time to connect the conductor 103 to conductor 103a to effect energization of magnet 84 upon closure of contacts R18d to cause the latched keys to be released. Contacts 71a can be adjusted so that the make period is sufficient to permit contacts R18d to close and effect energization of the said magnet 84. The machine is now conditioned for further verifying operations.

An additional feature of the present machine comprises the provision of means whereby the film record can be analyzed to determine the presence of unwanted spots or imperfections in the spaces between the index point positions, which imperfections or spots would cause the statistical machines to function improperly, if not detected. To attain this, the brushes 101 of the commutator device are arranged so that the next adjacent segment is engaged thereby before disengagement of the first segment (see arrangement of conducting segments in timing chart). In this way the groups of relays UR1 to UR14, TR1 to TR14, etc. can be energized at any time during the sensing portion of the cycle to indicate the presence of unwanted spots or imperfections in the film records. It is understood from the above description that the recorded data designations are effective to operate certain ones of the control relays AR to AB, BR to BB, and CR to CB whenever the said data designations are sensed. By means of the operated contacts AR1 to AB1, BR1 to BB1, and CR1 to CB1, which represent or indicate the data values of the sensed designations upon their operation, and the described commutator device 99 and the associated control circuits, the sensed data values are compared to the data stored or represented by the contacts A of the keyboard section. Now, by providing the segments 100 of the said commutator device to overlap the next adjacent segment, as indicated in the timing chart, the brushes 101 engaging these segments can complete circuits through different ones of the relays of the groups UR1 to UR10—HR1 to HR10, depending upon the times at which the contacts AR1 to AB1, etc. are operated. Thus, any unwanted marks or designations, capable of influencing the control operations of statistical machines, cause circuits to be completed through certain of the relays of the group AR1 to UR10, etc. to effect an indication of disagreement between the designations sensed on the records and the predetermined verifying data represented by the operated keys of the keyboard section as described hereinabove. The described control circuits are also effective to indicate any unwanted marks or designations formed in color by causing certain of the relays UR11 to UR14, TR11 to TR14, and HR11 to HR14 to be energized, whenever the unwanted colored designations are sensed, similarly as set forth hereinabove.

While there has been shown and described and pointed out the fundamental novel features of the invention as applied to a single modification it will be understood that various omissions and substitutions and changes in the form and details of the device illustrated and in its operation may be made by those skilled in the art, without departing from the spirit of the invention. It is the in-

tention, therefore, to be limited only as indicated by the scope of the following claims.

What is claimed is:

1. A machine of the character described for verifying statistical data on records comprising means for feeding individual records having data designations disposed thereon which are formed in different colors, means for sensing the colored data designations on the said records, a group of individual control means, means controlled by the sensing means for controlling the said individual control means in accordance with the color and data values of the sensed designations respectively, settable means for setting up predetermined color and data designations to which the sensed designations should conform, means cooperating with said individual means and settable means for comparing the sensed and said predetermined color and data designations, and means controlled by the comparing means to indicate the relationship of both the color and data values of the said compared designations.
2. A machine of the character described for verifying statistical data on records comprising means for feeding individual records having data designations disposed thereon which are formed in different colors, said designations on each record being disposed at different positions thereon to denote the different values of the data, means for sensing the colored data designations on each record, means controlled by the sensing means for initiating differentially timed impulses in accordance with the data and color values of the sensed designations, a plurality of data and color representing circuits and means for conditioning the circuits to represent predetermined data and color values to which the sensed designations should conform, means operated in timed relationship with the feeding means for routing the initiated timed impulses through the said conditioned circuits, means controlled by the impulses routed through the said circuits to determine the relationship of the said sensed and predetermined data and color values, and means controlled by the last named means for indicating the said determined relationship of the verified data and color values.
3. A machine of the character described for verifying statistical data on records comprising means for feeding individual records having colored data designations disposed thereon, means for sensing the said colored data designations on each record comprising a light source, light responsive means and elements for rendering the light responsive means selectively responsive to certain colors of the data designations, said light responsive means being conditioned by the light rays modified by the colored data designations, means controlled by the light responsive means in accordance with the data values of the sensed colored data designations, means for representing the color values of the sensed colored data designations consisting of a plurality of control circuits, one for each color of the designations formed on the records and of means controlled by the light responsive means for selecting and energizing those circuits corresponding to the colors of the sensed designations, settable means for representing predetermined color and data values to which the sensed designations should conform, distributor means, including control means operated in timed relationship with the feeding means, cooperating with the first mentioned controlled means, the said selected control circuits and the said settable means to de-

termine the relationship of the color and data values of both the sensed and predetermined data values, and means controlled by the said distributor means for indicating the said determined relationship of the verified color and data values.

4. A machine of the class described for verifying statistical data on records having data designations of different colors disposed thereon, means for feeding individual records, means for sensing the colored data designations on each record, individual means controlled by the sensing means for representing the color and data values of the sensed designations, a plurality of color and data representing circuits, one for each of the color

values and data values which the designations may have, means for selecting certain circuits of said plurality, to represent predetermined color and data values to which the sensed designations should conform, means rendered effective, whenever a sensed designation is not in agreement with a selected color or data representing circuit to which it should conform, to energize the color or data representing circuit pertaining to the sensed non-conforming color or data value, and means adapted to be controlled by the respective color and data representing circuits, for indicating the non-conforming color or data values.
